(57) **CLAIM**

The ornamental design for a display screen or portion thereof with graphical user interface, as shown and described.

DESCRIPTION

FIG. 1 is a front view of a display screen or portion thereof with graphical user interface showing the new design; and, FIG. 2 is a front view of a second embodiment thereof. The broken lines showing the display screen and various features of the graphical user interface are included for the purpose of illustrating environment of the claimed design. The broken lines form no part of the claimed design.

1 Claim, 2 Drawing Sheets

Treatment Options		Siteman Hospital		
All (10) ENDOWED REGIMENS-CUPRO (9) G. 10047 70415.07		Group ID: 10047		
☐ Cancer Type: Colon ☐ Pathology: Adenocarcinoma ☐ Role: Treatment ☐ Line of Treatment: First line ☐ Lead Treatment: Imatinib ☐ Regimen: Siteman Endowed Regimen (CUPRO) ☐ Drug: Imatinib ☐ Regimen ID: 10047 ☐ Regimen Name: CUPRO ☐ Protocol: CUPRO ☐ Regimen Description: CUPRO		Support ☒ Opposition ☐ None ☐		
Regimen Name: ☐ Endorsed OMICS Regimen: ☐ OMICS Guidance: ☐ OMICS Justification:		Level of Unselected Evidence: ☐ Estimated Outcome: ☐		
☐ Imatinib, Leucovorin, and Mesna (CUPRO) ☐ Regimen ID: 10047 ☐ Regimen Description: Overexpression of EGFR has been described with improved response to imatinib.		Level of Unselected Evidence: A4 ☐ Estimated Outcome: Median OS: 23.1 months ☐ Cost: \$20,000.00 ☐		
☐ Fluorouracil, Leucovorin, and Irinotecan (CUPRO) ☐ Regimen ID: 10047 ☐ Regimen Description: Overexpression of EGFR has been associated with improved response to irinotecan.		Level of Unselected Evidence: A4 ☐ Estimated Outcome: Median OS: 15.8 months ☐ Cost: \$20,000.00 ☐		
☐ Capecitabine ☐ Regimen ID: 10047 ☐ Regimen Description: N/A		Level of Unselected Evidence: A4 ☐ Estimated Outcome: Median OS: 8.5 months ☐ Cost: \$20,000.00 ☐		
☐ Capecitabine and Bevacizumab ☐ Regimen ID: 10047 ☐ Regimen Description: N/A		Level of Unselected Evidence: A4 ☐ Estimated Outcome: Median OS: 15.6 months ☐ Cost: \$20,000.00 ☐		
☐ Capecitabine ☐ Regimen ID: 10047 ☐ Regimen Description: EGFR is over expressed in ovarian cancer (A4)		Level of Unselected Evidence: N/A ☐ Estimated Outcome: N/A ☐ Cost: \$0,000.00 ☐		
☐ Capecitabine and Carboplatin ☐ Regimen ID: 10047 ☐ Regimen Description: Overexpression of the EGFR can cause resistance to platinum-based therapies.		Level of Unselected Evidence: A4 ☐ Estimated Outcome: Median OS: 14.2 months ☐ Cost: \$20,000.00 ☐		
☐ Capecitabine, Oxaliplatin and Bevacizumab ☐ Regimen ID: 10047 ☐ Regimen Description: Overexpression of the EGFR can cause resistance to platinum-based therapies.		Level of Unselected Evidence: A5 ☐ Estimated Outcome: Median OS: 15.6 months ☐ Cost: \$20,000.00 ☐		
☐ Fluorouracil, Leucovorin, and Mesna (CUPRO) ☐ Regimen ID: 10047 ☐ Regimen Description: Overexpression of the EGFR can cause resistance to platinum-based therapies.		Level of Unselected Evidence: A4 ☐ Estimated Outcome: Median OS: 16.0 months ☐ Cost: \$20,000.00 ☐		
☐ Fluorouracil, Leucovorin, Carboplatin (CUPRO) ☐ Regimen ID: 10047 ☐ Regimen Description: Overexpression of the EGFR can cause resistance to platinum-based therapies.		Level of Unselected Evidence: A4 ☐ Estimated Outcome: Median OS: 15.4 months ☐ Cost: \$20,000.00 ☐
